UNITED STATES PATENT OFFICE.

CURTIS J. ROTHERMEL, OF NEW HOPE, PENNSYLVANIA.

ROLL-PROTECTOR.

No. 894,906.

Specification of Letters Patent.

Patented Aug. 4, 1908.

Application filed November 9, 1907. Serial No. 401,521.

To all whom it may concern:

Be it known that I, CURTIS J. ROTHERMEL, a citizen of the United States, residing at New Hope, in the county of Bucks and State 5 of Pennsylvania, have invented a new and useful Roll-Protector, of which the following is a specification.

This invention relates to roll protectors for use upon the ends of rolls of roofing material 10 such as felt, tar paper, tin, etc.

The object of the invention is to provide caps for the ends of a roll and which are shaped to fit within the roll opening so as to brace the ends of the roll and prevent the roll 15 from becoming crushed.

Another object is to provide end caps designed to be connected by a single flexible device disposed to be non-detachably secured to one of the caps, the other cap having 20 means for temporarily engaging said connecting means so as to hold the parts in proper relation.

A still further object is to provide caps having their edge portions so finished that they 25 will not bite into or otherwise mar the material forming the roll to which the caps are applied.

Another object is to provide a protector requiring the use of but a single connecting 30 device, the same being readily detachable from one of the caps of the protector so that said protector can be conveniently removed from the roll.

With these and other objects in view the 35 invention consists of certain novel features of construction and combinations of parts which will be hereinafter more fully described and pointed out in the claims.

In the accompanying drawings is shown 40 the preferred form of the invention.

In said drawings: Figure 1 is a vertical section showing the protector applied to a roll of roofing material. Fig. 2 is a plan view of the protector. Fig. 3 is a similar view of 45 the lower cap of the protector. Fig. 4 is an enlarged section through one edge portion of one of the caps.

Referring to the figures by characters of 50 reference, 1 designates a roll of roofing material, the same being provided with the usual opening 2 through the center thereof and the protector constituting the present invention is designed to be placed upon the ends of the roll and within said opening. This protector 55 consists of two preferably circular disks 3 and

4 having their peripheral portions inturned or folded as at 5 so that it becomes impossible for said portions to bite into the ends of the roll and mutilate or otherwise mar the same. A circular depression 6 is formed in 60 each of the disks and is so proportioned as to fit snugly within one end of the opening 2, said depressions being preferably tapered as shown so that they can be readily inserted into the opening. Apertures 7 are formed 65 within the central portion of one of the caps while the depressed portion of the other cap has oppositely extending tongues 8 struck therefrom, there being an opening 9 formed between the tongues as shown. A connecting 70 device 10 preferably of wire has one end portion inserted through the openings 7 and twisted so as to form a positive connection with the cap 4. The other end of this connecting device is designed to be extended 75 throughout the opening 2 and aperture 9 and after it has been pulled taut so as to bind the two caps upon the ends of the roll the same is wrapped around and under the tongues 8 after which said tongues can be pressed in 80 wardly so as to bind upon the flexible device 10 and prevent it from slipping.

As indicated in Fig. 1 receptacles 11 may be placed within the opening 2, the same being designed to hold the various articles necessary to secure the material of the roll upon a roof. Where these receptacles are used the flexible device 10 is extended between them and the wall of the opening 2. If, however, the receptacles 11 are not employed the device 10 can be extended on a straight line from one cap to the other.

A roll structure such as hereinbefore described is particularly designed for use in connection with rolls of paper, felt, etc.

What is claimed is:

The combination with a roll having a central opening extending therethrough; of circular disks bearing upon the ends of the roll, each disk being formed in a single piece of 100 metal having an inwardly struck circular central portion or depression projecting into the opening, the depressed portion of one of the disks having a pair of apertures in the bottom thereof and the depressed portion of 105 the other disk having a central aperture and oppositely extending outstruck tongues integral with the disk, the peripheral portion of each disk being rolled and constituting a bearing bead, and a flexible connection be- 110

tween the depressed portions of the two disks, said connection being looped through the pair of apertures in one of the disks and threaded through the central aperture in the 5 other disk, one end of said connection being wrapped upon the tongues, said tongues being depressible into their disk to retain the connection in engagement therewith.

In testimony that I claim the foregoing as my own, I have hereto affixed my signature in the presence of two witnesses.

CURTIS J. ROTHERMEL.
